RECEPTACLE FILLING DEVICE

Adolph J. Lippold, Milwaukee, Wis., assignor to
 Cherry-Burrell Corporation, Chicago, Ill., a
 corporation

Application May 4, 1942, Serial No. 441,637

2 Claims. (Cl. 226—124)

1

This invention relates to improvements in devices for filling receptacles, such as milk bottles, with fluid.

It is the primary object of this invention to provide an improved receptacle filling valve, in which valve is comprised of relatively few, inexpensive, sanitary, easily assemblable and disassemblable elements; in which a resilient valve sleeve is adapted to constitute the fluid flow passage intermediate the reservoir and the valve seat element and also supply the pressure to seal the valve elements one against another; in which a condensate deflector element protects the receptacle engaging portion of the improved valve from contamination by condensate; in which the air vent tube of the improved valve is provided with means to prevent the easy drainage of liquid therefrom; in which at least one of the condensate deflector elements associated with the improved valve is positioned outwardly of the resilient valve sleeve; in which the valve seat element and resilient valve sleeve are not directly connected one to another; in which the relatively movable valve plug and valve seat element are provided with guide means to maintain them in proper relative operative position; and in which the resilient valve sleeve is sealed to the supply reservoir in a unique manner.

The foregoing and other objects will be more apparent and more readily understood when read in connection with the drawings of the preferred embodiments of the present invention in which:

Figure 1 is a vertical central sectional view of the improved receptacle filling valve.

Fig. 2 is a plan view taken along line 2—2 of Fig. 1.

Figure 3 is a fragmentary vertical sectional view of the improved filling valve showing a modified vent tube support.

Figure 4 is a plan view taken along line 4—4 of Figure 3.

Figure 5 is a vertical central sectional view of a modification of the improved receptacle filling valve.

Figure 6 is a fragmentary vertical sectional view of a further modification of the improved filling valve.

Figure 7 is a plan view of a modified embodiment of the improved valve.

Figure 8 is a vertical sectional view taken along line 8—8 of Figure 7.

Referring to the drawings, in which like numerals identify like parts, 10 represents a reservoir for liquid, the bottom of which reservoir is

2

provided with a series of openings for receiving valves for filling receptacles. Each of the openings is defined by a downwardly turned flange 11, as shown with respect to one opening in Figure 1 of the drawings.

A vent tube supporting spider 12, as shown in Figure 1, centrally supports a vent tube 13 in the opening defined by the dependent flange 11. An apertured valve plug element 14 is fixed to the lower extremity of the tube 13 with the aperture of the plug 14 communicating with the open passage of the vent tube 13. The lower extremity of the aperture of the plug 14 is defined by a restricted orifice 15, by virtue of which orifice the easy flow of liquid and gas through the vent tube 13 is partially controlled.

The spider 12, as shown in Figure 1, which has the nature of a spring clip and which is made of flexible, resilient material, is provided with four symmetrically positioned feet 16 to rest upon the interior of the bottom of the reservoir 10. The lower portion of the arms of the spider 12 is so formed as to extend into and engage the flange 11, thus centering the supporting spider 12 with respect to the opening in the bottom of the reservoir 10. The engagement between the vent tube 13 and the spider 12 is secured by the abutting relation between the annular flange 17 on the vent tube 13 and the top of the arms of the spider 12 when assembled in operative position, as shown in Figures 1 and 2.

In the views of the modified embodiment of the applicant's invention, as shown in Figures 3, 4, 5, 7 and 8, the spider for supporting the vent tube 13 consists of a central hub 18 provided with four radially extending arms 19. The arms 19 are each provided with a depending portion adapted to centeringly fit into the conical opening in the lower portion of the tank 10 formed by the independent inwardly directed flange 11. Each of the arms 19 is also provided with an outwardly extending foot portion 52 which rests upon the inner face of the bottom of the tank 10.

The hub 18 is swiveled on a collar 20 carried by the vent tube 13. The vent tube 13 is prevented from traveling downwardly through the hub 18 of the vent tube supporting spider by the removable clip 21 mounted in an annular groove 22 in the collar 20 and abutting the upper end 50 of the hub 18. In the modification of the invention shown in Figure 3, the upward vertical motion of the vent tube 13 through the hub 18 is prevented by the flange 23 at the lower extremity of the collar 20 on the vent tube 13 and below the position occupied by the hub 18 of the sup-

porting spider when the vent tube and supporting spider are arranged in operative position within the supply reservoir 10.

The valve element 14 carried by the vent tube 13 below the opening defined by the flange 11 in the bottom of the tank 10 is provided with upper and lower frusto-conical faces 24 and 25, respectively. The upper frusto-conical face 24 constitutes a valve face and engages a complementary valve seat consisting of the lower terminus of the cylindrical valve element or sleeve 26. The element or sleeve 26 is provided at its upper extremity with an upwardly and downwardly extending condensate deflector flange 27 having an upwardly turned outer edge 28 and a drain spout 29, all as clearly shown in Figure 1.

Adjacent the juncture between the sleeve 26 and the flange 27, the flange 27 is provided with a downwardly directed, embossed, annular depression 30, the upper and hollow face of which serves as a seat for the inwardly directed edge 31 defining the opening in the lower wall 32 of the resilient freely flexible bulb-like valve sleeve 33. The bulb 33 is compressed between the bottom of the tank 10 and the flange 27 of the valve sleeve 26 to form a fluid passage connecting the opening in the bottom of the tank 10 and the opening in the sleeve 26.

The inwardly directed edge 34 defines the opening in the upper wall 35 of the bulb 33 and engages the bottom of the tank 10 and the downwardly turned flange 11, which latter element is securely encompassed by the edge 34, the edge 34 being slightly distended thereby.

The bulb 33 is preferably made of resilient freely flexible rubber of a grade similar to that used in the bottle mouth sealing rings or gaskets commonly used on bottle filling valves of the type constituting the subject matter of this invention.

An upwardly and outwardly directed rib 36 is provided on the outer face of the upper wall 35 of the bulb 33. The rib 36 sealingly engages the flat surface of the bottom of the reservoir 10. The sealing engagement between the rib 36 and the bottom of the reservoir 10 prevents accumulated moisture from readily passing from the bottom of the tank 10 into the interior of the bulb 33. A similar but downwardly directed rib 37 is provided on the outer face of the lower wall 32 of the bulb 33 to direct the accumulated condensate from the bulb 33 onto the condensate deflecting flange 27 carried by the sleeve 26 before such condensate reaches the point of juncture between the flange 27 and the inner edge 31 of the lower wall 32 of the bulb 33, all as clearly shown in Figure 1.

The bulb 33 is so constructed that, when compressed into operative position as shown in Figure 1, it will bias or press the valve seat at the lower extremity of the valve sleeve 26 against the valve face 24 of the plug 14 supported by the vent tube 13. The bulb 33 also constitutes the fluid passage between the opening in the bottom of the tank 10, as defined by the flange 11, and the passage through the sleeve 26.

A resilient bottle gasket or seal is provided to seal the mouth of a bottle to be filled by the improved valve mechanism. In the improved valve shown in Figure 1 a resilient ring-like gasket element 38, preferably made of rubber and snugly fitted over the lower portion of the sleeve 26, is provided. The upper wall of the element 38 abuts against portions of the lower face of the flange 27. The lower wall of the element 38 is adapted

to sealingly engage the mouth of a bottle or other receptacle during filling operations.

An outwardly and downwardly directed condensate deflector flange 39 formed integrally with the element 38 is provided at the juncture of the lower wall and the side wall of the element 38. The object of the flange 39 is to further protect the open mouth of the bottle or receptacle as it moves toward and away from filling position below the filling valve.

Although the embodiment of the invention shown in Figure 1 has been particularly referred to in the preceding description, the modified arrangement for supporting the vent tube 13 in operative position, as shown in Figures 3, 4, 5, 7 and 8, may readily be interchanged with the arrangement for supporting the vent tube 13, as shown in Figure 1, by the addition or deletion of the necessary collars, flanges and clips, all as previously described and as clearly illustrated in the various drawings.

In Figure 5, the opening in the bottom of the tank 10 is defined by a downwardly and outwardly directed flange 40 over which the inner edge 41 defining the opening in the upper wall 43 of the modified valve sleeve bulb 42 is distended to obtain a secure engagement therewith. The upper wall 43 abuttingly engages the bottom of the tank 10.

30 The valve sleeve 44, adjacent its upper extremity, is provided with an annular groove 45 in its outer periphery to receive the inner distended edge 46 defining the lower opening in the bulb 42. A condensate deflector 47 is carried by 35 the sleeve 44 but, unlike the embodiment of the invention shown in Figure 1, the deflector flange 47 is not formed integrally with the sleeve 44. Like unto the modified embodiment of the invention shown in Figure 1 and as described, the 40 bulb 42 also forms the fluid passage between the opening in the bottom of the tank 10 and the hollow valve sleeve 44 and also biases or urges the valve sleeve 44 into seating engagement with the valve plug 14.

45 In Figure 6 is shown an arrangement of a valve bulb 48, the upper inner edge of which abuts against the bottom of the tank 10 about the flange 11. The bulb 48 is provided about its outer mid-section with a condensate gutter or deflecting 50 flange 49 and, when the bulb 48 is compressed in a manner as would occur when the valve sleeve 50 is moved toward the tank 10, the outer and normally upwardly turned wall of the deflecting flange 49 will snap downwardly into a position as 55 shown by the dotted line 49' of Figure 6.

The bottle mouth gasket 38 of Figure 6 is also provided at its lower edge with an upwardly turned condensate deflector flange or gutter 51 similar in cross section to the flange 49. Both of 60 the flanges 49 and 51 function to protect the mouth of a bottle or receptacle from dripping condensate as the bottle or receptacle is moved into and away from filling position under the improved filling valve.

65 Figures 7 and 8 disclose several views of a further modification of the improved filling valve of the instant invention. The structural feature of chief importance which distinguishes the modified valve shown in Figure 8 from the disclosure 70 of the preceding figures is the provision of four guide arms or studs 53 fixed at their lower extremities in the upper end of the valve sleeve 54 and extending upwardly through the opening in the bottom of the tank 10, as defined by the flange 11, and extending upwardly in overlapping

relation to the hub 18 of the vent tube supporting spider between the bases of the radially extending arms 19.

Each of the four guide arms or studs 53 is of such dimension as to permit the free vertical reciprocation of the sleeve 54 but to limit any reciprocatory motion of the sleeve 54 when such motion is at an angle to the vertical axis of the vent tube 13. The guide arms 53, in order to accomplish such limitation in the motion of the sleeve 54, are slightly less in cross sectional dimension than the horizontal distance between the inner edge of the flange 11 and the outer edge of the hub 18. The guide arms 53 are also of such a length as to permit substantial contact between the guide arms 53 and the hub 18 when the sleeve 54 tends to move in a general vertical direction along a line other than parallel to the axis of the vent tube 13. As in the previously described modifications of the present invention, a resilient bulb 55 is interposed between the bottom of the tank 10 and the top of the sleeve 54 to urge or bias the lower end of the sleeve 54 which constitutes a valve seat against the valve plug 14 and to also establish a passage for controlled fluid flow between the opening in the tank defined by the flange 11 and the opening in the sleeve 54.

The invention, as just described, provides an improved receptacle filling valve or device having relatively few and inexpensive sanitary parts easy to assemble and disassemble, and in which a resilient bulb-like element is interposed between a unitary valve sleeve and an opening in a supply reservoir for the dual purpose of maintaining the valve and valve seat in normally sealed relationship one to another and to provide a passage for the conducting of fluid from the interior of the supply reservoir to the receptacle to be filled.

A further advantage of the improved valve, as just described, is the provision of an arrangement of valve elements so that the resilient valve bulb, which constitutes part of the fluid flow passage of the valve, is sealingly secured in operative position to the supply reservoir in a very simple and sanitary manner which facilitates the assembly and disassembly of the device.

Although several preferred embodiments of the present invention have been described, various modifications thereof may present themselves to those skilled in the art upon reviewing the preceding description and the drawings referred to therein. The invention is, therefore, not to be restricted except in so far as is necessitated by the prior art and the spirit of the appended claims.

The invention is hereby claimed as follows:

1. In a device for filling containers from an

apertured reservoir, a valve plug, means for supporting said plug below an aperture in said reservoir, said means including a support spider having a central element located centrally with respect to said aperture in said reservoir, a valve seat element intermediate said plug and said reservoir and adapted to be moved into and out of seating engagement with said plug, resilient means intermediate said reservoir and said valve seat element for biasing said valve seat element toward said valve plug, and guide means carried by said valve seat element extending closely adjacent said central element of said support spider for guiding said valve seat element when moving into and out of engagement with said valve plug and limiting the lateral motion of said valve seat element with respect to said valve plug.

2. In a device for filling containers from an apertured reservoir, a valve plug, means for supporting said plug below an aperture in said reservoir, said means including a support spider having a central element located centrally with respect to said aperture in said reservoir, a valve seat element intermediate said plug and said reservoir and adapted to be moved into and out of seating engagement with said valve plug, resilient means intermediate said reservoir and said valve seat element for biasing said valve seat element toward said valve plug, and guide means carried by said valve seat element extending through said resilient means, through said aperture in said reservoir in close proximity to the edge of said aperture and passing closely adjacent said central element of said support spider for guiding said valve seat element when moving into and out of engagement with said valve plug and limiting the lateral motion of said valve seat element with respect to said valve plug.

ADOLPH J. LIPPOLD.
